UNITED STATES PATENT OFFICE

136,826

DESIGN FOR AN OPTICAL COUNTING DEVICE

John T. Armbruster, Niagara Falls, N. Y., assignor
to Spencer Lens Company, Buffalo, N. Y., a
corporation of New York

Application May 28, 1943, Serial No. 110,314

Term of patent 14 years

To all whom it may concern:

Be it known that I, John T. Armbruster, a citizen of the United States, residing at 237 74th Street, Niagara Falls, in the county of Niagara and State of New York, have invented a new, original, and ornamental Design for an Optical Counting Device, of which the following is a specification, reference being made to the accompanying drawings, forming a part thereof.

Fig. 1 is a front perspective view of an optical counting device embodying my design;

Fig. 2 is a front view thereof; and
Fig. 3 is a side view thereof.

The back of the design is plain and the opposite side presents substantially the same appearance as the side shown.

I claim:

The ornamental design for an optical counting device, substantially as shown and described.

JOHN T. ARMBRUSTER.
